UNITED STATES PATENT OFFICE.

CHARLES J. JORGENSEN, OF MILWAUKEE, WISCONSIN.

COLOR-SCALE.

SPECIFICATION forming part of Letters Patent No. 709,328, dated September 16, 1902.

Application filed February 17, 1902. Serial No. 94,484. (No model.)

To all whom it may concern:

Be it known that I, CHARLES J. JORGENSEN, a citizen of the United States, residing at Milwaukee, in the county of Milwaukee, and State of Wisconsin, have invented new and useful Improvements in Color-Scales, of which the following is a specification.

My invention relates to color-scales; and the object of the same is to construct a rational scale of tertiary colors containing all possible important shades of color which can be obtained by mixing the three primary colors yellow, red, and blue. To obtain these shades directly by the mixing of the primary colors is impossible and only leads to a chaos of colors which cannot be arranged in any system which is of use to artisans as a guide in matching or dyeing.

The system used by me is fully described in this specification and claimed, and illustrated in the accompanying drawing, forming a part thereof, in which the figure is a table showing the list of secondary and primary colors and a rational scheme for arranging the tertiary colors obtained by mixing in pairs the secondary colors and the primaries.

In this specification when I speak of "secondary colors" I mean those obtained by mixing two primary colors, and when I speak of "tertiary colors" I mean those containing all three primary colors.

In the table shown in the drawing there is a wide column to the left which is designated by the letter A. The column A is divided up into eighteen rectangular spaces by horizontal lines B, which rectangles are numbered consecutively from "1" to "18." In the rectangle "1" is printed "Yellow," in the seventh is printed "Red," and in the thirteenth is printed "Blue." Between "1" and "7" are arranged the principal secondary colors formed by mixing yellow and red in varying proportions. These colors are arranged in rational order, the one containing the largest per cent. of yellow standing next to yellow. Between "7" and "13" are arranged in rational order the colors obtained by mixing red and blue, and after "13" comes the colors obtained by mixing blue and yellow. It is obvious that the number of secondary colors, of which the table contains fifteen, could be increased by interpolating between the different colors in the

table as between what I term "orange-yellow" and "yellow-orange."

As before stated, the object of my invention is to obtain a rational scale of the tertiary colors. The method of attaining this object is shown by the portion of the table to the right of column A, which contains eleven columns D, divided up into rectangles by the prolongation of the horizontal lines B.

Standing in the heads of the columns D are the names of the colors which stand below "Red" in the column A. Now yellow can be mixed with each of the colors which stand at the head of the first five columns to produce tertiary colors. These new tertiary colors are denoted by two dots; but as no broken color would result from the mixture of yellow with the colors which head the next six columns only secondary colors would result. No dots are placed in the rectangles standing next below. A new tertiary color would result from mixing the next color below yellow (orange-yellow) with each of the colors standing at the heads of the columns D. The same thing is true of all of the colors standing above "Red." But red can only be mixed with the colors heading the last five columns to form tertiary colors. This is true also of all colors standing above "Blue," which exhausts the series of possible combinations forming tertiary colors. To obtain a scale of tertiary colors the members of which would differ from each other by less than the members of the series constructed as above described, it would only be necessary to form a larger number of secondary colors between each pair of primaries and then mix them in pairs in the same manner as before to form tertiary colors.

After forming the series of tertiary colors as above indicated, to construct a color-chart a table is arranged as shown in the drawing; but the corresponding tertiary color is printed in each of the rectangles D in which dots now appear. The first column A forms no essential part of the chart, but might be filled out with the corresponding colors, if desired.

Having described my invention, what I claim as new, and desire to secure by Letters Patent, is—

1. The method of constructing a scale of tertiary colors which consists in first taking the three primary colors yellow, red, and

- blue and forming the principal secondary colors by mixing them in pairs, and then taking each of said secondary colors in turn and mixing it with the primary lacking in the 5 said secondary color taken and with every other secondary color which contains said lacking primary, substantially as described.
2. In a color-chart, a graduated series of colored figures comprising the secondary colors which can be formed by mixing in pairs the three primary colors, yellow, blue and red and the principal tertiary colors formed by mixing in pairs the said secondary colors, substantially as described.
- 10 3. In a color-chart, a series of colored figures arranged in rational sequence and com-

prising tertiary colors which are formed by taking the three primary colors, yellow, red and blue and mixing them in pairs to form secondary colors, and then taking each of 20 said secondary colors in turn and mixing it with the primary lacking in the said secondary color taken, and with every other secondary color which contains said lacking primary, substantially as described.

25 In testimony whereof I have hereunto set my hand in presence of two subscribing witnesses.

CHARLES J. JORGENSEN.
